UNITED STATES PATENT OFFICE.

VALENTIN M. KLUGE, OF NEW YORK, N. Y.

REVOLVING HAND-FAN.

1,171,727.

Specification of Letters Patent. Patented Feb. 15, 1916.

Application filed June 16, 1914. Serial No. 845,422.

To all whom it may concern:

Be it known that I, VALENTIN M. KLUGE, a citizen of the United States, and a resident of New York, borough of Brooklyn, county 5 of Kings, and State of New York, have invented a certain new and useful Improvement in Revolving Hand-Fans, of which the following is a full, clear and exact specification.

10 This invention relates to a class of fans adapted to be carried by a person.

My invention has for its object primarily to provide a fan of a portable type so as to be conveniently used for fanning a person, 15 and in accordance therewith I provide a tubular handle having a shaft journaled in its upper end. On one end of the shaft is mounted the fan proper consisting of spirally twisted blades extending radially from 20 a common center so as to be revolved in unison when the shaft is rotated, and over the shaft is movably wrapped a flexible element, or cable adapted to drive the shaft by frictional contact therewith when the ends of 25 the cable are directed to and fro relatively to the shaft.

Another object of the invention is to provide within the tubular handle spring actuated means which is connected to one end of 30 the cable for forcing the cable in one direction; and still another object of the invention is to provide a manually operative lever which is fulcrumed to the handle and connected to the other end of the cable to force 35 the cable in an opposite direction against the tension of the spring actuated means whereby the drive shaft may be driven to revolve the fan for producing the required currents of air.

40 A further object of the invention is to provide a revolving hand fan wherein a number of its parts may be stamped from sheet metal so as to be susceptible of being made to sell at a very moderate price, and which may 45 be formed in various sizes and shapes.

A practical embodiment of the invention is represented in the accompanying drawings forming a part of this specification in which similar characters of reference indicate corresponding parts in all the views, the said invention being more fully described hereinafter and then pointed out in the claims at the end of the description.

50 In the drawings, Figure 1 is a front elevation of one form of revolving hand fan embodying my invention. Fig. 2 is an eleva-

tion showing one side of the fan. Fig. 3 is an elevation showing the opposite side of the fan. Fig. 4 is a front view of the spring used in the fan. Fig. 5 is a side view of the 60 spring. Fig. 6 is a side view of the sleeve used in the fan. Fig. 7 is a view of another side of the sleeve. Fig. 8 is a longitudinal section through the sleeve when applied to the handle of the fan. Fig. 9 is a top plan 65 of the straddle bar employed in the fan. Fig. 10 is a front view of the straddle bar. Fig. 11 is an edge view of the ring used in conjunction with the sleeve of the fan. Fig. 12 is a side view of the ring, and Fig. 13 is 70 a sectional elevation, partly in detail, of the fan showing a modified form of the spring actuated means thereof.

The revolving hand fan has a tubular handle 10 which is preferably made of sheet 75 metal formed in a tubular shape, and part of the upper end of the handle is cut-out, as at 11. In an upper part of the handle opposite to its cut-out 11 is a slot 12 disposed lengthwise of the handle, and through the 80 central part of the handle in proximity to the lower end of the slot is an opening 13. Also through the upper part of the handle opposite to the central part of the slot 12 are two spaced holes 14 and 14^a, and through 85 the upper end of the handle adjacent to its cut-out 11 are two registered openings 15 and 15^a. The tubular handle and these parts may be made by the use of cutting and forming dies according to any of the well-known methods. In the registered openings 15 and 15^a is a freely rotatable shaft 16 having a flattened, or substantially rectangular head 17 extending exteriorly of the 90 tubular handle. On this head 17 is held a 95 fan 18 having a number of spirally twisted blades 19 which are radially disposed from a common center, as 20, all of which are integrally formed by being stamped from a single sheet of metal. In order to hold the 100 fan 18 rigidly on the head 17 of the shaft 16, a clip, or straddle bar 21 is provided. The straddle bar 21 is substantially U-shaped, and this bar has a rectangular opening 22 in its central part through which the 105 part of the head of the shaft 16 between the fan and the handle 10 is disposed. The central parts of the arms of the straddle bar 21 are bent outwardly at right angles and then bent forwardly. The free ends of the 110 arms of the straddle bar are passed through two spaced openings 21^a in the center of

the fan, and these ends are then struck inwardly toward each other upon the center of the fan which will thereby be tightly clamped to the head of the shaft 16.

Serving to rotate the shaft 16 and the fan 18 in unison, around the central part of the shaft is movably wrapped, at 23, the upper part of a flexible element, or cable 24. The lower end portion of the cable 24 is disposed downwardly through the tubular handle 10 and passed through the slot 12 thereof, and this end of the cable is fastened to the eye 25 provided on one end of a spring, as 26. The spring 26 is preferably in the form of a strip of wire normally extending through the lower part of the slot 12 of the handle 10, and this strip is disposed upwardly on an incline across the interior of the handle. The upper end portion of the spring 26 is spirally twisted around a pin, as 27, which is disposed through the holes 14 and 14^a of the handle 10, and the upper free end of the spring rests against the adjacent part of the inner surface of the handle. The tension of the spring 26 will thus normally serve to force the cable 24 in a direction toward the lower part of the handle.

For the purpose of allowing the cable 24 to be moved in frictional contact with the shaft 16 against the tension of the spring 26 so that the cable will be forced back and forth, the upper end of the cable is attached to a hook 28 on the upper end of a hand-lever 29. The lever 29 is in the form of a rod having its central part bent to provide an eye, as 30, and the lower part of the lever is disposed outwardly on an incline so as to be spaced some distance from the handle 10 of the fan. The lever 29 is fulcrumed, at 31, by pivoting its eye between extending ears, or lugs 32 of a sleeve, or band 33 provided approximately midway of the handle 10. The sleeve 33 is preferably made of sheet metal, and this sleeve is secured to the handle of the fan by a countersunk indent, as 34, forced into the opening 13 of the handle. Part of the sleeve 33 at about a quadrant thereof relatively to its ears 32 is bent outwardly from the handle to form a spaced portion, as 35, and through this spaced portion is a substantially rectangular aperture 36 in which is clamped the angular ends 37 of a split ring 38 having its end parts disposed between the spaced portion 35 of the sleeve and the wall of the handle. The ring 38 is thereby held to the sleeve so that its opening will be transversely disposed with respect to the handle of the fan.

To operate the fan the handle 10 is gripped in one hand of the person, and one of the fingers is passed through the ring 38. One or more of the other fingers of the operator then grasp the lower end of the hand-

lever 29 which in turn is directed toward the handle 10. The lever 29 will thereby be swung on its fulcrum for moving the upper part of the hand-lever outwardly from the handle 10, and the cable 24 will be guided upwardly through the slot 12, through the handle, and through the cut-out 11. The lower part of the spring 26 and its eye 25 will also be moved in an upward direction against the tension of the spring, and when the force on the hand-lever is relaxed the tension of the spring 26 will force the cable 24 in a reverse direction. By operating the hand-lever in this manner at frequent intervals, the friction of the cable with the shaft 16 will cause the shaft and the fan 18 to revolve at a suitable speed to produce sufficient currents of air for fanning the person.

In Fig. 13 is shown a form of the device wherein the spring 26 is dispensed with, and instead, a plug, as 39 Fig. 13, may be secured in the lower part of the handle 10. In the top of the plug 39 is driven a staple 40, and to the staple is fastened the lower end of an elastic band, as 41, of rubber, or other similar material. The upper end of the elastic band is connected to the lower end of the cable 24 so that when the fan is operated, as above described, the cable will be guided upwardly through the handle 10 in frictional contact with the shaft 16 and against the tension of the elastic band when the hand-lever is moved in the manner explained, and by providing the elastic band of suitable tension it will cause the cable to be moved in an opposite direction when the pressure on the lever is released. The shaft 16 and the blades 19 of this form of the fan may thus be revolved at a suitable speed.

In the foregoing description, I have embodied the preferred form of my invention, but I do not wish to be understood as limiting myself thereto, as I am aware that modifications may be made therein without departing from the principle, or sacrificing any of the advantages of this invention; therefore I reserve to myself the right to make such changes as fairly fall within the scope of the appended claims.

Having thus described my invention, I claim as new and desire to secure by Letters Patent:—

1. A revolving hand fan, comprising a handle, a shaft journaled in the upper part of the handle, a plurality of spirally twisted blades disposed radially from a common center rigidly held on the shaft, a flexible element having a part thereof movably wrapped around the shaft, spring actuated means on the handle, and connected to one end of the flexible element, a band mounted on the handle and a hand-lever fulcrumed to the band, a pivot carried by the band, 120

said hand-lever being formed with an eye pivotally engaged with said pivot, one end of the hand-lever being connected to the other end of the flexible element and the 5 other end of said hand-lever being spaced from the handle so that when forced toward the handle the upper end of the lever will be swung to guide the flexible element in one direction in frictional contact with the shaft and against the tension of the spring 10 actuated means which will reversely guide the flexible element when the pressure on the handle is relaxed whereby the shaft and said blades will be revolved to produce currents of air. 15

2. A revolving hand fan, comprising a tubular handle, a slot in the handle, a shaft journaled in the upper part of the handle, a plurality of radially disposed spirally 20 twisted blades, means rigidly holding the blades on the shaft, and in spaced relation to the handle, a cable having a part thereof movably wrapped around the shaft, spring actuated means within the tubular handle 25 and operable through the slot, and connected to one end of the cable, and a hand-lever fulcrumed to the handle of the fan, one end of the hand-lever being connected to the other end of the cable, and the other 30 end of said hand-lever being spaced from the handle so that when forced toward the handle the upper end of the lever will be swung to guide the cable in one direction in frictional contact with the shaft and against 35 the tension of the spring actuated means

which will reversely guide the cable when the pressure on the handle is relaxed whereby the shaft and said blades will be revolved to produce currents of air.

3. A revolving hand fan, comprising a 40 tubular handle, a shaft journaled in the upper part of the handle, a plurality of spirally twisted blades radially disposed from a common center rigidly held on the shaft, a cable having a part thereof movably wrapped around the shaft within the handle, a vertical slot in the handle, a spring within the tubular handle, said spring being anchored at one end to the handle and connected to one end of the cable at its other 45 end, and a hand-lever fulcrumed to the handle of the fan, one end of the hand-lever being connected to the other end of the cable, and the other end of said hand-lever being spaced from the handle so that 50 when forced toward the handle the upper end of the lever will be swung to guide the cable in one direction in frictional contact with the shaft against the tension of the spring which will reversely guide the cable 55 when the pressure on the handle is relaxed whereby the shaft and said blades will be revolved to produce currents of air.

This specification signed and witnessed this fifteenth day of June, A. D. 1914.
